By *A. A. Audrey, Jr.* Attorney

UNITED STATES PATENT OFFICE.

BERNARD R. KABIGTING, OF OAKLAND, CALIFORNIA.

NAILING IMPLEMENT.

1,406,027.

Specification of Letters Patent. Patented Feb. 7, 1922.

Application filed March 18, 1921. Serial No. 453,221.

To all whom it may concern:

Be it known that I, BERNARD R. KABIGTING, a citizen of the United States, residing at Oakland, in the county of Alameda 5 and State of California, have invented certain new and useful Improvements in Nailing Implements; and I do hereby declare the following to be a full, clear, and exact description of the invention, such as will 10 enable others skilled in the art to which it appertains to make and use the same.

The invention provides a tool embodying a magazine and nail race and a hammer, whereby the nails are automatically fed into 15 proper position and driven home, the nails being held and guided throughout the driving operation, thereby preventing marring a finished surface by failure to strike the nail when aiming a blow thereat. The blows 20 are also delivered squarely upon the head of the nail, thereby driving the same straight without liability of bending the nail as frequently occurs by reason of the blow being delivered to one side of the center of the 25 head.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor details of construction may be resorted to 35 without departing from the nature of the invention.

Referring to the accompanying drawings forming a part of the specification,

Figure 1 is an elevation of a tool embodying the invention,

Figure 2 is a central longitudinal section thereof,

Figure 3 is a horizontal section on the line $w-w$ of Figure 2, and

Figure 4 is a modification.

Corresponding and like parts are referred to in the following description and designated in the several views of the drawings by like reference characters.

The tool embodies a casing 1 and a cap 2 slidably mounted upon the upper end 50 of the casing. A core 3 is secured within the casing 1 and has a central longitudinal opening extending therethrough. The upper portion of the opening is enlarged, as

indicated at 4, and the lower portion is constricted, as designated at 5. A hammer or plunger 6 is slidably mounted in the enlarged portion 4 of the opening and its driving head is reduced, as indicated at 7, to operate in the constricted portion 5 of the opening. The hammer or plunger 6 is connected with the cap 2 so as to move longitudinally therewith. An expandable helical spring 8 is interposed between the upper end of the core 3 and the closed end of the cap 2 and normally holds the hammer in withdrawn or driving position. The core 3 is preferably made in similar longitudinal halves or sections in each of which the opening for the hammer or plunger is partly formed. Dowels 9 hold the parts or sections of the core in proper position. Suitable fastenings, as screws 10, hold the core and casing in proper position. The driving end of the core 3 is tapered, whereby positioning of the tool is made easy. A nail race 11 is formed in the outer side of the core 3 and extends in a helical or spiral direction. The delivery end of the nail race 11 communicates with the constricted portion 5 of the hammer opening to insure delivery of the nails thereto. The helical formation of the nail race insures a positive movement of the nails without a too rapid feed and accommodates a great number of nails because of the extent of the race. The upper end of the nail race 11 communicates with an opening 12 formed in a side of the casing 1. A flat spring 14 is disposed in the constricted portion 5 of the hammer opening opposite the delivery end of the nail race 11 and engages and supports the nails to prevent their premature discharge from the tool.

In practice, nails 13 are supplied to the nail race 11 through the opening 12 and after the nail race has been filled, the casing 1 is turned upon the core 3 to close the opening 12. When it is required to drive a nail, the tool is positioned with its point opposite the spot where the nail is to be driven. A quick movement of the cap 2 operates the hammer or plunger, whereby the nail is driven home by repeated blows delivered upon the head thereof by reciprocating the hammer or plunger in a manner well understood. It will be understood that each blow of the hammer or plunger is delivered squarely upon the head of the nail, thereby obviating any possible injury to a highly 105 110

polished surface such as would be occasioned by the hammer missing the nail or slipping therefrom. Moreover, the nail is held and directed throughout the driving operation and is prevented from bending or leaning to one side or the other as is the case when driving nails in the usual way and which is objectionable.

In the modification shown in Figure 4, 10 the trap 2 is provided in a side with an opening 15 to receive a box 16 for holding a quantity of nails in reserve to supply the nail race when the latter has become exhausted or needs replenishing.

15 What is claimed is:

1. A tool of the character specified comprising a casing a core within the casing and having a longitudinal opening and a helical nail race, a cap slidable on the cas-

ing, and a hammer in the longitudinal opening having connection with said cap.

2. A tool of the character specified comprising a casing having an opening in a side thereof, a cap slideable on the casing, a sectional core within the casing having a longitudinal opening formed partly in each of the sections and having a helical nail race in its outer side closed by the casing, a plunger mounted in the longitudinal opening of the core, and an expansible helical spring 25 30 disposed between the cap and core.

In testimony whereof I affix my signature in presence of two witnesses.

BERNARD R. KABIGTING.
